UNITED STATES PATENT OFFICE

BISHOP M. CRAWFORD, OF ST. LOUIS, MISSOURI

GUNLOCK

Application filed April 8, 1929. Serial No. 353,465.

This invention relates to gunlocks and it consists in the novel construction, combination and arrangement of parts and cooperating elements herein shown, described and 5 claimed.

An object of the invention is to provide an improved gunlock for embodiment in a gun of the over- and under-barrel type having the hammers arranged and mounted in 10 such a manner that they strike forwardly with central energy instead of laterally and characterized by ease of operation in cocking. In accomplishing this object the hammers or strikers are pivoted on fulcrums 15 near the lower part of the gunlock and are mounted in such relationship to the sears that the firing pins are struck as the hammers or strikers are thrown forwardly by their springs located vertically in the gunlock rearwardly of the barrels.

Another object of the invention is to provide a construction, combination and relationship of parts whereby outstanding ease of operation is obtained in guns of the over- 25 and under-barrel type.

Another object is to provide an improved gunlock embodying all of the improved features of construction and characterized by all of the advantages herein disclosed, reference being made to the accompanying drawing in which

Fig. 1 is a side elevation of my improved gunlock.

Fig. 2 is a vertical longitudinal sectional view.

Fig. 3 is a rear end elevation, the trigger plate and the upper portion of the frame being shown in section.

Fig. 4 is a vertical sectional view showing 40 the firing pins.

My invention is embodied in a gunlock comprising a frame or receiver 1 for a gun of the over- and under-barrel type. The over- and under-barrels 2 are pivotally connected to the gunlock or supported in connection with the gunlock on a pivot 3.

For the upper barrel a firing pin 4 is provided and for the lower barrel a firing pin 5 is located directly below the pin 4.

For the upper barrel a hammer or striker

6 is pivoted on a fulcrum 7 and is provided with a laterally extended arm 8 (Fig. 3) arranged and designed to strike the rear end of the upper firing pin 4 when the upper barrel is to be fired. The hammer or striker 6 55 is driven by a spring 9 located vertically in a spring barrel 10 in the frame or receiver 1 between the rear ends of the barrels 2 and the hammer or striker 6. A guide plunger comprising a stem 11 extending upwardly 60 into the lower end of the spring 9 and a head 12 forming an abutment for the lower end of said spring 9 constitute means for actuating the hammer or striker 6 by said spring 9. The lower pointed end of the head 65 12 of the plunger guide operates in a cavity 13 in the forward arm of the hammer or striker 6. A shoulder 14 is formed on one side of the hammer or striker 6 for engagement with the sear 15.

The sear 15 is pivoted on a fulcrum 16 and has a shoulder 17 on its under side arranged to engage with the shoulder 14 on the hammer or striker so as to hold the latter retracted (Fig. 2). A spring 18 is interposed 75 between the frame or receiver 1 and a shoulder 19 on the sear 15 above the fulcrum 16 and the power and energy of said spring is utilized to actuate the sear in a direction to engage the shoulder 17 with the shoulder 14 80 to hold the hammer or striker 6 cocked.

The hammer or striker 6 is cocked by a cocking plunger 20 supported for sliding movements in the frame or receiver 1 and having its rear end contacting with an arcuate cam 21 on the hammer or striker 6. The cam 21 is in front of the fulcrum 7 and the cocking plunger abuts against said cam 21 above the plane of said fulcrum 7 so that when the cocking plunger is forced rearwardly as shown 90 (Fig. 2) the hammer or striker 6 will be cocked by engaging the shoulder 14 thereon with the shoulder 17 on the sear 15. A return spring 22 for the cocking plunger is provided, the same encircling said cocking plunger and having its rear end abutting against a part of the frame or receiver 1 and its forward end abutting against a shoulder 23 on said cocking plunger.

A cocking cam 24 is provided for operating 100

the cocking plunger 20 and is pivoted on a fulcrum 25 in such a way that when the cocking cam is swung downwardly to the position shown (Fig. 2) the cocking plunger will be forced rearwardly to cock the hammer or striker 6.

A trigger 26 for releasing the sear 15 from engagement with the hammer or striker 6 is provided. Said trigger is mounted on a pivot 27 supported by the trigger plate 28 which is a separate piece from the frame or receiver 1.

For the lower firing pin 5 a hammer or striker 29 is provided and may be pivoted on the same fulcrum 7 on which the hammer or striker 6 is pivoted. This hammer or striker 29 has a lateral projection 30 designed and adapted to strike the lower striker pin 5 when fired. It will be understood that the sear 31 for the hammer or striker 29 is exactly like the sear 15 so that specific illustration of the sear 31 is unnecessary, as such illustration would be a mere duplication of the sear 15 as shown in Fig. 2. Likewise it will be understood that the hammer or striker 29 is operated by a spring mounted and otherwise in all respects similar to the spring 9 and that a plunger guide similar in all respects to the plunger guide 11-12 cooperates with the spring for operating the hammer or striker 29. The hammer or striker 29 is cocked by precisely the same form of cocking device as that shown and above described for cocking the hammer or striker 6. The lower rear end of the sear 31 is designed and adapted to be engaged by a part of a trigger 32 so as to be released in the same manner that the sear 15 is released by the trigger 26.

From the foregoing it must be apparent that the gun is cocked by operation of the cocking cams 24 and that the gun is fired by operating the triggers 26 and 32 to release the respective sears 15 and 31 from the respective hammers or strikers 6 and 29. These hammers or strikers are mounted on horizontal pivots at the lower part of the frame or receiver 1 and are driven in firing operations by vertical springs 9 located in vertical spring barrels at the rear of the gun barrels and in front of the respective hammers or strikers. Firing is accomplished by a straight-forward striking action of the hammers with centralized energy and the parts are arranged and cooperatively mounted so as to permit and obtain outstanding ease of operation in guns of the type mentioned, that is to say, in guns of the over- and under-barrel construction.

While the gunlock here illustrated and described is of particular utility in a gun of the over- and under-barrel type, its utility is not limited to such a combination.

I am aware that the construction, arrangement and relationship of parts may be varied within equivalent limits without departing from the nature and principle of the invention as defined by the appended claims.

What I claim and desire to secure by Letters Patent is:—

1. A gunlock for guns of the over- and under-barrel type comprising a frame or receiver, hammers or strikers pivoted on horizontal fulcrums near the lower side of the frame or receiver, springs mounted in the frame or receiver in front of the respective hammers or strikers for actuating the latter, sears pivoted in front of said hammers or strikers for engaging and holding the latter cocked, springs for actuating the sears downwardly into engagement with the hammers or strikers, and triggers for releasing the sears from said hammers or strikers. 75

2. A gunlock for guns of the over- and under-barrel type comprising hammers or strikers pivotally mounted for straightforward striking movements, a sear for each of said hammers or strikers pivotally mounted vertically above the points at which the hammers or strikers are pivoted, means whereby said sears will hold the respective hammers or strikers cocked, springs mounted vertically in planes in front of the pivotal mountings of said hammers or strikers for operating the latter, and triggers for releasing the sears from the hammers or strikers. 80

3. A gunlock including a hammer pivoted on a horizontal fulcrum for striking movement, a sear pivoted on a horizontal fulcrum at its one end in front of said hammer and adapted to engage therewith, and a trigger element pivoted on a horizontal fulcrum at its front end, its upper surface rearwardly of its fulcrum arranged and adapted to contact with the rear end of the sear to raise the sear and release the hammer. 95

4. A gunlock including a hammer pivoted on a horizontal fulcrum for forward striking movement, a sear pivotally mounted on a horizontal fulcrum at its one end vertically above the hammer fulcrum in front of said hammer and adapted to engage therewith, and a trigger element pivotally mounted on a horizontal fulcrum at its front end, its upper surface rearwardly of its fulcrum arranged and adapted to contact with the rear end of the sear to raise the sear and release the hammer. 105

5. A gunlock including a hammer pivoted on a horizontal fulcrum for forward striking movement a sear pivoted on a horizontal fulcrum at its one end in front of said hammer and adapted to engage therewith, a spring adapted to engage a shoulder on the sear positioned upwardly and rearwardly from the sear fulcrum, and a trigger element pivoted on a horizontal fulcrum at its front end, its upper surface rearwardly of its fulcrum arranged and adapted to contact with the rear end of the sear to raise the sear and release the hammer. 110

6. A gunlock including a hammer lever of the first class pivotally mounted on a hori- 125

zontal fulcrum for forward striking movement, said hammer having a forwardly extending spring engaging arm and an upwardly extending hammer arm, a spring mounted vertically in front of the hammer arm and bearing downwardly against the top of said forwardly extending arm, a cam on said forwardly extending arm upwardly from said fulcrum, and a plunger adapted to 10 engage said cam to cock the hammer.

7. A gunlock including a hammer lever of the first class pivotally mounted on a horizontal fulcrum for forward striking movement, said hammer element having a forwardly extending spring engaging arm and an upwardly extending hammer arm, a spring mounted vertically in front of the hammer arm and bearing downwardly against the top of said forwardly extending arm, and a sear 15 pivoted on a horizontal fulcrum at its one end in front of said hammer arm and adapted to engage therewith.

8. A gunlock including a hammer lever of the first class pivotally mounted on a horizontal fulcrum for forward striking movement, said hammer element having a forwardly extending spring engaging arm and an upwardly extending hammer arm, a spring mounted vertically in front of the hammer 20 arm and bearing downwardly against the top of said forwardly extending arm, a sear pivoted on a horizontal fulcrum at its one end vertically above the hammer fulcrum in front of said hammer arm and adapted to engage therewith, and a trigger element pivoted on a horizontal fulcrum at its front end, its upper surface rearwardly of its fulcrum arranged and adapted to contact with the rear end of the sear to release the hammer.

40 9. A gunlock including a hammer lever of the first class pivotally mounted on a horizontal fulcrum for forward striking movement, said hammer element having a forwardly extending spring engaging arm and an upwardly extending hammer arm, a spring mounted vertically in front of the hammer arm and bearing downwardly against the top of said forwardly extending arm, a cam on 45 said forwardly extending arm upwardly from said fulcrum, a plunger adapted to engage said cam to cock the hammer, a sear pivoted on a horizontal fulcrum at its front end in front of said hammer arm and adapted to engage therewith, a spring adapted to engage 50 a shoulder on the sear positioned upwardly and rearwardly from the sear fulcrum, and a trigger element pivotally mounted on a horizontal fulcrum at its front end, its upper surface rearwardly of its fulcrum arranged 55 and adapted to contact with the rear end of the sear to raise the sear and release the hammer.

BISHOP M. CRAWFORD.
